Ernst Waldschmidt

UNITED STATES PATENT OFFICE

2,227,046

ELECTRON VALVE

Ernst Waldschmidt, Berlin, Germany, assignor,
by mesne assignments, to Loewe Radio, Inc., a
corporation of New York

Original application January 31, 1933, Serial No.
654,378. Divided and this application November
20, 1935, Serial No. 50,760. In Germany
February 2, 1932

2 Claims. (Cl. 250—27.5)

This invention relates to indirectly heated metallic vapor cathodes.

Indirectly heated metallic vapor cathodes consist, as well known, of a heating element, an insulating member surrounding the heating element, an equipotential layer provided on the insulating member, and an emissive coating provided on the equipotential layer, which coating may consist, for example, of an alkaline earth 5 oxide or of oxidized tungsten, and be activated or made capable of emission by the application, by atomization, of barium.

It has been found that cathodes of this nature are frequently accompanied by acoustical disturbances, such as humming noises and the like. Thorough investigations have shown these disturbances to be created by the fact that in the course of production of the cathodes above referred to the metallic vapor is deposited not only 10 on the highly emissive layer to be activated, but on the insulating member as well. By reason of this deposit located outside of the actual highly emissive layer shunts are produced, and there is caused a detrimental subsidiary emission. The 15 present application is a divisional application of application Ser. No. 654,378 filed January 31, 1933, describing the same matter.

The subject matter of the invention is a cathode, in which these disturbances are avoided. 20 According to the invention, the cathode is formed in such fashion that the coating of atomized activating material formed outside of the actual emissive area is unable to act in disturbing fashion.

It has been found that these sources of error 25 may be avoided, if the equipotential layer is so formed and arranged, that the coating produced at the ends of the insulating tube are unable to cause shunts.

According to the invention the equipotential surface consists of two tubes fitted one within the other, one of the tubes being longer than the other.

An embodiment of the invention is illustrated 30 in the drawing.

In the drawing the equipotential surface consists of two tubes fitted one within the other. The outer tube 2 is longer than the inner tube 6. 35 The highly emissive coating, 3 the insulating tube and 4 the filaments with the current leads 5, 9 and 10 two electrodes, e. g. grid and anode.

Owing to this particular form of the equipotential layer a metallic coating formed on the ends 40 of the insulating tube is unable to cause shunts, because no emissive layer will be deposited on the part 7 of the insulating tube between the ends of the tubes 2 and 6.

I claim:

1. An electron valve containing an indirectly heated cathode, control electrode and output electrode, said cathode comprising an elongated heater element, an insulating tube member completely surrounding the heater element, a first metallic equipotential surface surrounding the insulating tube member having a length materially less than the length of the insulating tube member, the ends of said first metallic surface being spaced substantially equidistant from the 5 ends of the insulating tube member, a second metallic equipotential surface surrounding the first metallic equipotential surface having a length greater than the length of said first equipotential surface and less than the length of the insulating tube member, the ends of said second metallic equipotential surface being spaced substantially equidistant from the ends of the insulating tube member and from the ends of the 10 first equipotential surface, and a layer of electron emissive material deposited on the outer surface of said second equipotential surface whereby a portion of said insulating tube member extending beyond the ends of said first equipotential surface will be shielded by said second 15 equipotential surface.

2. An electron valve containing an indirectly heated cathode, control electrode and output electrode, said cathode comprising an elongated heater element, an insulating tube member completely surrounding the heater element, a first metallic equipotential surface surrounding the insulating tube member having a length materially less than the length of the insulating 20 tube member, the ends of said first metallic surface being spaced substantially equidistant from the ends of the insulating tube member, a second metallic equipotential surface surrounding the first metallic equipotential surface having a length greater than the length of said first equipotential surface and less than the length of the insulating tube member, the ends of said second metallic equipotential surface being spaced substantially equidistant from the ends of the insulating tube member and from the ends of the 25 first equipotential surface, and a layer of electron emissive material deposited on the outer surface of said second equipotential surface whereby a portion of said insulating tube member extending beyond the ends of said first equipotential surface will be shielded by said second 30 equipotential surface.

3. An electron valve containing an indirectly heated cathode, control electrode and output electrode, said cathode comprising an elongated heater element, an insulating tube member completely surrounding the heater element, a first metallic equipotential surface surrounding the insulating tube member having a length materially less than the length of the insulating 35 tube member, the ends of said first metallic surface being spaced substantially equidistant from the ends of the insulating tube member, a second metallic equipotential surface surrounding the first metallic equipotential surface having a length greater than the length of said first equipotential surface and less than the length of the insulating tube member, the ends of said second metallic equipotential surface being spaced substantially equidistant from the ends of the insulating tube member and from the ends of the first equipotential surface, said insulating tube member and equipotential surfaces being maintained in position by frictional engagement with 40 each other, and a layer of electron emissive material deposited on the outer surface of said second equipotential surface whereby a portion of said insulating tube member extending beyond the ends of said first equipotential surface will be shielded by said second equipotential surface.

ERNST WALDSCHMIDT.
